UNITED STATES PATENT OFFICE.

WILLIAM C. P. BALDWIN, OF HOLYOKE, MASSACHUSETTS.

COMBINED BUTCHER'S APRON AND FROCK.

No. 884,063.

Specification of Letters Patent.

Patented April 7, 1908.

Application filed November 20, 1907. Serial No. 402,991.

To all whom it may concern:

Be it known that I, WILLIAM C. P. BALDWIN, a citizen of the United States of America, and resident of Holyoke, in the county of 5 Hampden and State of Massachusetts, have invented certain new and useful Improvements in a Combined Butcher's Apron and Frock, of which the following is a full, clear, and exact description.

10 The object of this invention is to provide a combined frock and apron very desirable for use by butchers, provision and grocery men, so made that one front portion of the garment may cover, conceal and protect the 15 other, with capability of reversal whereby after one of the apron members may have become soiled, the other fresh and clean apron member may be presented outermost, a further object being to provide peculiarly arranged means for the confinement of the 20 apron members in their overlapping relations while being worn with the garment fronts in suitably taut or unwrinkled condition, with provisions whereby such confining means 25 may be most easily manipulated.

As a result aimed at by the present invention, the necessity of buttons or metallic fastenings of any description is avoided, and the garment is most desirable and acceptable to 30 provision men because of the simplicity and inexpensiveness thereof, because of its great convenience to its wearer, and especially because of the ease with which it may be laundered.

35 The invention consists in the combined frock and double apron having the formations, relative arrangements, characteristics and appliances as hereinafter described in conjunction with the accompanying drawings and set forth in the claims.

In the drawings.—Figure 1 is a view of the garment in its superficial aspect or spread out condition. Figs. 2 and 3 are similar front views of the garment as worn, showing reversed relations and arrangements of the side portions or apron members and the confining means therefor. Fig. 4 is a cross sectional view as taken on line 4—4, Fig. 2.

In the drawings.—A represents the back portion of the garment, the lower portion 40 of which constitutes a skirt understood as being suitably long so as to extend more or less, as may be desired, below the fynes.

B B represent side portions or apron members continuous of the back A and its skirt, and adapted to have relations the one

overlapping the other at the front and to extend around to the sides of the person as will be apparent in Figs. 2, 3 and 4. Said apron members have their edges from about 60 the waist line at 4, 4, extended on convergently inclined lines 12, 12, to their junction with the collar edge 13 of the garment. The said garment has hand slits a a about at the waist line, and approximately at the regions 65 where the apron members B B adjoin or merge into the back B. The said apron members have strings or tapes d d secured at the apexes 15 of their angular portions,—the fastening thereof being by stitching, 70 tying, or otherwise,—whereby when the garment is worn with one apron member overlaid by the other the string d which extends from the edge of the relatively inner apron member may be by the hand passed 75 through the adjacent hand slit around the garment, horizontally, to be connected with the other string d, connected to and extended from the edge of the relatively outer apron member; and it will be apparent that due 80 to the formation of the upper portions of the apron members with the convergently inclined edges 12, 12, as shown, and the connecting strings or tapes d, d as shown, the breast portions of the garment will be 85 constrained in unwrinkled or substantially taut conditions.

It will be evident that after usage of the 90 combined frock and apron whereupon the relatively outer apron member B becomes soiled and unsightly, the fastenings may be easily loosened, the formerly innermost apron member may be brought outermost, and the one which had been exposed will be concealed; and provisions of the hand 95 slits a not only render it possible and also most convenient to effect the fastening of the aprons in their selected relations, but they also enable the wearer of the garment to have access by both of his hands to the 100 pockets of his trousers or coat.

There being an entire absence of buttons or metallic buckles or other fastening, the laundering of this garment is consequently more readily accomplished, and there being 105 no such buttons or metallic fastenings, liability thereof of becoming torn off or broken in laundering is avoided, as well also as from rusting of the fabric.

I claim:

110 A combined frock and apron, comprising a back portion, the lower part of which con-

stitutes a skirt, similar side portions or apron members continuous with the back and skirt thereof, adapted to completely overlap, either over the other, and to extend 5 around to the sides of the person, said apron members having their edges from about the waist line convergently inclined to their junction with the collar edge of the garment, said garment having a hand-slit at each side 10 at about the waist line and approximately at the regions where the apron members adjoin the back, and each apron member carrying a string at the apex of its angular

portion, the points of attachment of said strings, and said hand-slits, being substantially in alinement, the string of the inner apron member passing through the hand-opening adjacent the outer apron member to the exterior of the garment. 15

Signed by me at Springfield, Mass., in 20 presence of two subscribing witnesses.

WILLIAM C. P. BALDWIN.
